(57) CLAIM

We claim the ornamental design for sports apparel, as shown and described.

DESCRIPTION

FIG. 1 is a front view of the sports apparel;

FIG. 2 is a rear view thereof;

FIG. 3 is a left side view thereof;

FIG. 4 is a front perspective view thereof; and,

FIG. 5 is a rear perspective view thereof.

The band comprises a first color. The body portion of the sports apparel does not include the band and comprises a second color that is different than the first color.

A right side view of the sports apparel not shown in the FIGURES is a mirror image of the left side view shown in FIG. 3 without the dotted lines.

The dot-dashed lines and the dotted lines in the FIGURES depict portions of the sports apparel that form no part of the claimed design. The unshaded surfaces bounded by the dot-dashed lines and the dotted lines form no part of the claimed design.
